(57) **CLAIM**

The ornamental design for a toilet bowl, as shown and described.

DESCRIPTION

FIG. 1 is a perspective view of front, top and right side of a toilet bowl according to our new design;

FIG. 2 is a perspective view of rear, top and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged cross sectional view at 9-9 thereof; and,
FIG. 10 is an enlarged cross sectional view at 10-10 thereof.
The portions of the article in broken lines are shown for
illustrative purposes only and form no part of the claimed
design.

The uneven broken lines represent disclaimed boundaries of
the claimed design.
